UNITED STATES PATENT OFFICE.

ROBERT W. HARDIE, OF NEW YORK, N. Y.

METHOD OF SHAPING METAL BODIES.

No. 877,077.

Specification of Letters Patent.

Patented Jan. 21, 1908.

Application filed June 17, 1907. Serial No. 379,527

To all whom it may concern:

Be it known that I, ROBERT W. HARDIE, a citizen of the United States, and a resident of the city of New York, borough of Manhattan, in the county and State of New York, have invented a new and Improved Method of Shaping Metal Bodies, of which the following is a full, clear, and exact description.

10 This invention relates to a method of shaping the bodies of metal receptacles, such as barrels, milk cans and similar objects, and has for its primary object to provide a simple and effective method of expanding a blank 15 to a predetermined extent at different parts, so as to form a body having parts of different diameters, and when desired of different thickness or cross section.

20 A further object of the invention is to provide a suitable blank adapted to be used in forming said bodies.

25 Other objects relating to the method of producing the specific construction of different vessels will be understood from the following description and accompanying drawings, in which similar characters of reference indicate similar parts throughout the several views, and wherein

30 Figure 1 is a vertical section of a partly formed tubular blank having vertical corrugations of varying depth; Fig. 2 is a plan of the blank shown in Fig. 1; Fig. 3 is a vertical section of the shell of a bilge barrel with the corrugations removed; Fig. 4 is a perspective view partly broken away, of a blank showing a breast, neck and bowl partially formed; Fig. 5 is a perspective view partly broken away of the blank shown in Fig. 4, with the closed end of the neck portion removed and the upper portion of the neck provided with corrugations of varying 40 depth; Fig. 6 is a cross section of a milk can breast, neck and bowl, taken on the line 6—6 of Fig. 7; and Fig. 7 is a side elevation of the 45 milk can breast, neck and bowl shown in Fig. 6.

In Figs. 1, 2, and 3 my invention is illustrated as applied in forming the shell of a barrel, and in the remaining figures as applied in forming the breast, neck and bowl of a milk can.

50 This invention is employed in shaping the shell of a bilge barrel by first providing a tubular blank 1 with longitudinal corrugations 2. These corrugations are tapering and diminish gradually in extent from their

central portion to their ends, the extent of the corrugations being proportioned to the extent to which it is desired to expand the blank in diameter. The corrugations may 60 be formed by rollers having intermeshing ribs, or they may be stamped or otherwise formed in the blank. The length of the corrugations may be varied as desired so as to extend to the ends of the blank or to any 65 point removed from said ends. In forming the corrugations the metal is stretched and reduced in cross section to any extent desired. If the blank is of uniform thickness the central portion thereof when corrugated 70 will be thinner than the cross section of the outer portion of the blank. The central portion may, however, be made of the same thickness as the outer portion when stretched by making the original blank of greater 75 thickness or cross section at the center. By making the corrugations of greater depth at their center and diminishing toward their ends, the metal is stretched so as to form a structure having different diameters at different parts.

After the corrugations have been so formed and the metal stretched as desired, the blank is expanded by rolling or pressing out the corrugations, making a shell of the character indicated in Fig. 3, having a central bilge and contracted ends.

The invention may be applied in making the breast, neck and bowl of a milk can by first taking a sheet of metal, preferably round 90 in outline, and forming therein by the ordinary drawing process and the use of dies, a tubular blank 4, having a closed end 5. Tapering corrugations 6 extending longitudinally of the blank are formed in the body portion 7 95 of the blank, and the blank then expanded by pressing or otherwise forcing the corrugated portion of the blank outward into a dome shaped structure, such as shown in Fig. 4. The closed end 5 of the blank is cut away, 100 and that end of the blank fluted to form corrugations, preferably tapering, in the inner and outer surface of the blank, as shown in Fig. 5, and the corrugated end of the blank then pressed outward to remove the corrugations 105 and form a flaring bowl or mouth 11, as shown in Figs. 6 and 7. A plain annular surface is left in the blank between the corrugations 6 and 8. In such construction the plain portion of the blank forms a neck 10 110 which retains its original diameter and cross section, while the bowl and breast are re-

duced in cross section due to the stretching caused in forming the corrugations. The method of expanding the end of the blank into a bowl or flaring flange is especially effective, in that thereby all liability of splitting the end, and the expensive operation of spinning and its attendant annealing processes are avoided. By means of such operation the neck is made of any desired thickness or cross section, regardless of the corresponding dimension of the breast or bowl, and adapted to withstand any strains to which it may be subjected.

The method herein described for stretching a blank is effective, moreover, for the reason that as one rib of a roller or die meshes with two adjacent ribs of an opposite roller or die, said adjacent ribs form anvils or plates to support the blank, while the intermeshing rib of the other roller or die presses that portion of the blank intermediate said adjacent ribs into the recess between them, and stretches said portion independently of the balance of the blank, thereby guarding against unequal strains and fractures. The means employed for forming the corrugations and pressing or rolling them out when formed so as to expand the blank may be of any suitable character, and form no part of the invention claimed herein. Nor is the method or means for forming the initial tubular blank any part of this invention. A blank made tubular by any means or method other than that described herein may be used without departing from my invention.

Bodies of receptacles of various kinds may be formed by the method herein shown and described, that cannot be produced by the drawing or spinning processes now used. And even structures now produced by drawing and spinning can be far more cheaply and quickly produced by the method described herein. In shaping the bodies of metal receptacles it sometimes becomes necessary to use soft metal in order that it may be readily or properly spun into shape, as is the case in spinning the breast, neck and bowl of a milk can in one piece. Consequently, when the cans are in use the neck is too soft to stand the strain caused by jamming the covers into the necks, and the necks become stretched. Whereas by means of the process described herein spinning is unnecessary, and metal much firmer than that now used can be employed for such purpose, making the necks of the cans much stronger than those of cans now manufactured.

Having thus described my invention, what I claim as new and desire to secure by Letters Patent is:

1. The method of shaping metal bodies, which consists in fluting the end of a tubular blank to form corrugations in its inner and outer surface, at the same time stretching the corrugated portion and reducing it in

thickness, then pressing out the corrugations to form a flaring flange.

2. The method of shaping metal bodies consisting in fluting the end of a tubular blank to form tapering corrugations, at the same time stretching the corrugated portion and reducing it in thickness, and then pressing out the corrugations to flare the end of the blank.

3. The method of shaping metal bodies consisting in corrugating the end of a tubular blank, forming other corrugations in the body of the blank spaced from the end corrugations, at the same time stretching the corrugated portions, then pressing out the corrugated portions to form a flaring end and expanded body with an intervening contracted neck.

4. The method of shaping metal bodies, consisting in corrugating the end of a tubular blank, forming other corrugations in the body of the blank spaced from the end corrugations, at the same time stretching the corrugated portions, then pressing out the corrugations to form a flaring end, an expanded body, and an intermediate contracted neck of greater thickness than the mean thickness of the body.

5. The method of shaping metal bodies consisting in forming tapering, longitudinal corrugations in a tubular blank, beginning at a point removed from the end of the blank, at the same time stretching the corrugated portion, and then pressing out the corrugations to form an expanded body having parts of different diameters and a contracted neck having a greater thickness than the mean thickness of the body.

6. The method of shaping metal bodies, consisting in forming longitudinal corrugations in a tubular blank at a point or points where it is desired to enlarge it, at the same time stretching the corrugated portion and then pressing out the corrugations to expand the corrugated portion of the blank in diameter.

7. The method of shaping metal bodies, consisting in forming longitudinal corrugations in a partially formed blank, at the same time stretching the corrugated portion, and then pressing out the corrugations to expand the corrugated portion of the blank in diameter.

8. The method of shaping metal bodies which consists in forming tapering longitudinal corrugations in a tubular blank at a point or points where it is desired to enlarge it, at the same time stretching the corrugated portion and then pressing out the corrugations to expand the corrugated portion of the blank unequally in diameter.

9. A tubular blank for use in making the bodies of vessels by a stretching process, the said blank being provided at one end with a circumferential series of corrugations which

may be expanded into a flare, and having its body provided with longitudinal corrugations spaced from the end corrugations, and adapted to be pressed out to form an expanded body.

- 5 10. A blank for use in making the bodies of vessels by a stretching process, the body of said blank being provided with a plain portion, and a body portion having a mean thickness less than that of the plain portion, and provided with longitudinal corrugations

beginning at the terminal of the plain portion; the said corrugations being adapted to be pressed out to expand the corrugated portion of the blank unequally in diameter. 15

In testimony whereof I have signed my name to this specification in the presence of two subscribing witnesses.
